A new invention is disclosed in this patent, which relates to apparatus for the manufacture of concrete and apparatus for use therewith. The invention is particularly concerned with apparatus for the manufacture of concrete, and more particularly with apparatus for the manufacture of concrete in which the entrained or contained air in the mass of aggregate is withdrawn or exhausted therefrom whilst said mass is being subjected to mixing only in the wet state within a mixing chamber sealed from the atmosphere so as to produce a concrete which will be very dense in structure and strong owing to the absence of voids or pores usually present in concrete mixed in the ordinary way.

UNITED STATES PATENT OFFICE

1,968,691

MANUFACTURE OF CONCRETE AND APPARATUS FOR USE THEREWITH

Arthur Cyril Knipe, Westminster, London, England, assignor to Modern Concrete Development Company, Limited, London, England

Application November 20, 1933, Serial No. 698,741
In Great Britain July 5, 1932

8 Claims. (Cl. 83—73)

This invention relates to the manufacture of concrete wherein the entrained or contained air in the mass of aggregate is withdrawn or exhausted therefrom whilst said mass is being subjected to mixing only in the wet state within a mixing chamber sealed from the atmosphere so as to produce a concrete which will be very dense in structure and strong owing to the absence of voids or pores usually present in concrete mixed in the ordinary way.

Hitherto, the apparatus employed involved the use of a tiltable paddle type mixing chamber having a removable air tight cover or alternatively a non-tiltable rotary drum mixing chamber having a removable air-tight coverplate at one or both ends for sealing the opening or openings thereof.

The object of the present invention is to provide an improved method and apparatus for carrying out the manufacture of concrete.

According to the present invention, therefore, the ingredients forming the mass of aggregate are subjected to mixing within a tiltable revolving drum with removable air-tight cover forming the chamber from which the entrained or contained air in the wet mass of aggregate is withdrawn or exhausted during the mixing of said wet mass.

In apparatus for mixing concrete made according to this invention the revolving drum is provided with a single feed and discharge opening and is mounted in a frame so as to revolve about its own axis and to tilt about a horizontal axis, the drum being fed with the ingredients at one angle of tilt and adapted to subject the ingredients to the mixing process at another angle of tilt and to discharge the aggregate at still another angle of tilt.

The mixing position of the drum is one that is intermediate of the feeding and discharging positions and a movable door or cover is provided for closing the opening of the drum which is so arranged and carried upon the framing of the apparatus independently of the drum that whilst in its open or raised position said door or cover does not interfere with or foul the angular movement of the drum from the feeding position to the discharging position.

Means are provided for opening and closing the door or cover to the drum so that said door or cover can be lowered to close the opening of

the drum and seal it by its own weight when said drum is in the mixing position, thus forming an air-tight chamber within the drum. The door or cover is provided with suitable means and connection to the receiver, cylinder or other suitable part of an air pump or other source for withdrawing air from the mixing chamber to enable vacuum conditions to obtain for carrying out the de-aeration process. The door or cover is carried on a suitable movable arm supported on the framing of the apparatus and is so mounted on the arm as to be free to rotate with the drum and to align itself in the opening of the drum and adapt itself to any irregularity thereof.

Valve mechanism is also provided in the vacuum duct to the drum and so connected with and operable by the door opening and closing means whereby the valve closes the vacuum duct from atmosphere subsequent to the closing of the drum and opens the vacuum duct to atmosphere prior to the opening of the drum door.

The drum door opening and closing means is actuated by movement of a hand lever with a lost motion obtaining during initial movement of said hand lever which permits meanwhile destruction of the vacuum.

Referring to the drawings filed herewith:—

Fig. 1 is an elevation of one form of concrete mixing apparatus made in accordance with this invention;

Fig. 2 is a side elevation of same;

Fig. 3 is a detail view (to an enlarged scale) showing the door operating means, vacuum duct to the drum and the valve mechanism interposed therein.

2 is a framing mounted on wheels 3 and accommodated in the framing is a drum 4 supported by a vertical central spindle (not shown) mounted on a swing undercradle 5 and passing axially into the drum through the base thereof, the cradle being suspended by a solid trunnion 6 and a hollow trunnion 7 suitably accommodated in housings 8 and 9, respectively, secured to the framing 2. The cradle 5 is adapted to be swung about its trunnions by means of the toothed segment 10 engaging the pinion 12 which latter is operated by the hand wheel 13 mounted on the spindle 14 of the pinion 12, said spindle being accommodated in a housing 15 secured to the framing 2 and the toothed segment 10 being mounted fast on the

trunnion 6 of the cradle 5. In the hollow trunnion 7 is rotatably accommodated a spindle 16 which is driven by a sprocket wheel 17 thereon and on the inner end of said spindle and keyed thereto is a pinion 18 (Fig. 1) which engages a circular toothed rack 19 on the drum 4 whereby on rotation of the spindle 16 by the sprocket wheel 17, the drum is revolved about its axis. The sprocket wheel 17 is driven by a chain 20 from the driving sprocket 21 of a driving unit 22 suitably carried in the framing 2.

It will, therefore, be seen that the drum 4 can be tilted by actuation of the handwheel 13 whilst it is being rotated and arrangements are provided so that the said drum can be retained at three different angles of tilt, one being the filling position, another the mixing position and the other the discharging position.

On the outer end of the spindle 16 is provided another sprocket 23 for transmitting a drive to an overhead shaft 24 through a sprocket 25 and a friction clutch device 26 thereon. The shaft 24 is provided with two driving drums 27 for raising and lowering a feeding hopper 28 by wire ropes 29 passing over pulleys 30 shown more clearly in Fig. 1. The hopper 28 is carried by swing arms 31 (Fig. 1) mounted on a shaft 32 suitably carried in the framing 2.

A removable cover or door 33 is provided to the drum 4, said door being suspended upon an arm 34 and bracket 35 from a shaft 36 about which the arm can swing, the door 33 resting by its own weight upon and sealing the mouth of the drum 4 when closed and being supported in the open position by a crank arm 37 which when the door is closed is removed from contact with the arm 34 so that the door can rest upon the mouth of the drum as before-mentioned. This crank arm 37 is mounted fast upon the shaft 36 and its movement effected by manipulation of a hand lever 38 provided at one end of said shaft, such movement of the crank arm being that it has a lost motion after the door has closed upon the drum in order to disengage it from contact with the arm 34 and again when it is raised by the hand lever until it contacts with the arm 34.

The door 33 is mounted on the arm 34 by a hollow spindle 39 which is rotatable in a ball bearing 40 in a bearing 41 on the arm 34 whereby the door can rotate with the drum and the housing 41 is flexibly mounted upon the arm 34 by springs 42 so that the door can align itself in the mouth of the drum and adapt itself to any irregularities thereof. A rubber or other sealing gasket 43 is provided on the door to effect an air-tight fit.

A vacuum duct 44 having connection with a pump 45 is connected to the hollow spindle 39 of the drum door 33, said hollow spindle having open communication through the door to the interior of the drum, so that vacuum conditions can be obtained in the drum 4 by operation of the pump 45 which is driven from a pulley or sprocket 46 on the driving unit 22 by a chain 47 or the like.

The vacuum duct is provided with a filtering device 49 whilst the hollow spindle 39 of the door 33 is also provided with a filter 50.

Located in the vacuum duct is a valve casing 51 having a valve chamber 52 with a valve 53 therein controlling vacuum ports 54 and 55 and an atmospheric air port 56. This valve 53 is actuated by a stem 57 slidable in upper and lower guides 58 and 59. The outer end of the stem is connected to a valve operating lever 60 mounted fast upon the shaft 36, said lever being operable when the hand lever 38 is manipulated.

A water tank 61 is provided overhead with a feed pipe 62 through which water is adapted to be fed on to the ingredients as they fall from the hopper 28 into the drum 4.

The hand lever 38 is provided with a spring catch 63 for engaging a fixed toothed rack 64 so that said hand lever can be held in position.

The friction clutch device 26 on the shaft 24 is actuated by a pivoted lever 65 operable through a quadrant 66 on a shaft 67 movable by manipulation of a hand lever 68.

A ratchet wheel 69 is provided on the end of the shaft 24 adapted to be engaged by a hand operated pawl 70 for holding the hopper 28 in its raised position when necessary.

The hopper 28 is provided with an integral shoot 71 for directing the ingredients into the drum.

The connection 72 of the duct 44 with the hollow spindle 39 of the drum door 33 is a flexible one.

In operation, the revolving drum 4 is tilted by actuating the handwheel 13 to the filling position indicated by chain lines at x, Fig. 1, and the hopper containing the ingredients is raised to the position indicated by chain lines at y, Fig. 1, to discharge its contents into the drum, water also being allowed to mix with the ingredients. The revolving drum 4 is then tilted to the mixing position in which the drum is shown in full lines, 100 and the door or cover 33 lowered to seal the opening of the drum by operating the hand lever 38. Initial movement of said hand lever allows the door 33 to fall on to the drum mouth and simultaneously actuates the valve 53 through the lever 110 60 on the shaft 36, continued movement of the hand lever further actuates the valve so as to close the atmospheric port 56 of the valve chamber 52 in the vacuum duct 44 after the door has sealed the drum and thereby enable air to be withdrawn 115 from the drum by the pump 45 so as to establish vacuum conditions whilst the mixing operation takes place.

When the mixing has been completed it is, of course, essential that the vacuum in the revolving drum 4 should be destroyed before the door or cover 33 is raised and this is effected automatically as the hand lever 38 for opening the door is manipulated, first movement of said hand lever causing the valve 53 in the valve chamber 52 of the vacuum duct 44 to open the duct to atmosphere through the port 56 thus destroying the vacuum and continued movement of the hand lever bringing the crank arm 37 into contact with and thereby raising the door carrying arm 34 to lift the door or cover 33 clear of the revolving drum mouth. The revolving drum 4 is then tilted to the discharging position indicated by chain lines at z, Fig. 1, for the contents to be discharged for use whilst the drum is still revolving, said drum being 135 thereby completely emptied.

What I claim and desire to secure by Letters Patent is:—

1. Apparatus for manufacturing concrete comprising a framing, a tilttable revolvable drum having a single feed and discharge opening mounted in said framing, means for revolving the drum about its own axis, means for tilting the drum about a horizontal axis, a revolvable closure member for the drum and capable of revolving therewith, means on the framing for suspending said closure member independently of said drum, a vacuum duct supported by the framing and connected to vacuum creating means and to the drum closure member and adapted to communicate with

the interior of the closed drum through said closure member, means carried by the framing for receiving ingredients for the drum and operable for delivering said ingredients into the drum and means for manipulating the drum closure member to close and open the drum.

2. Apparatus for manufacturing concrete comprising a framing, a tilttable revolvable drum having a single feed and discharge opening mounted in said framing, means for revolving the drum about its own axis, means for tilting the drum about a horizontal axis, a revolvable closure member for the drum and capable of revolving therewith, means on the framing for suspending said closure member independently of said drum, a vacuum duct supported by the framing and connected to vacuum creating means and to the drum closure member and adapted to communicate with the interior of the closed drum through said closure member, a valve in said vacuum duct, means carried by the framing for receiving ingredients for the drum and operable for delivering said ingredients into the drum, means for manipulating the drum closure member to close and open the drum, actuation of the said drum closure manipulating means automatically operating the valve in the vacuum duct.

3. Apparatus for manufacturing concrete comprising a framing, a tilttable revolvable drum having a single feed and discharge opening mounted in said framing, means for revolving the drum about its own axis, means for tilting the drum about a horizontal axis, a revolvable closure member for the drum and capable of revolving therewith, means on the framing for suspending said closure member independently of said drum, a vacuum duct supported by the framing and connected to vacuum creating means and to the drum closure member and adapted to communicate with the interior of the closed drum through said closure member, means carried by the framing for receiving ingredients for the drum and operable for delivering said ingredients into the drum and means for manipulating the drum closure member to close and open the drum, said manipulating means being adapted to automatically destroy vacuum conditions in the drum immediately prior to movement of the drum closure member in opening said drum.

4. Apparatus for manufacturing concrete comprising a framing, a tilttable revolvable drum having a single feed and discharge opening mounted in said framing, means operable from a driving unit of the apparatus for revolving the drum about its own axis, hand actuated means for tilting the drum about a horizontal axis, a revolvable closure member for the drum and capable of revolving therewith, means on the framing for suspending said closure member independently of said drum, vacuum creating means operable by the driving unit, a vacuum duct supported by the framing and connected to said vacuum creating means and to the drum closure member and adapted to communicate with the interior of the closed drum through said closure member, means carried by the framing for receiving ingredients for the drum and operable for delivering said ingredients into the drum and means for manipulating the drum closure member to close and open the drum.

5. Apparatus for manufacturing concrete comprising a framing, a tilttable revolvable drum having a single feed and discharge opening mounted in said framing, means for revolving the drum about its own axis, means for tilting the drum

about a horizontal axis, a revolvable closure member for the drum and capable of revolving therewith, means on the framing for suspending said closure member independently of said drum, a vacuum duct supported by the framing and connected to vacuum creating means and to the drum closure member and adapted to communicate with the interior of the closed drum through said closure member, means carried by the framing for receiving ingredients for the drum and operable for delivering said ingredients into the drum and means for manipulating the drum closure member to close and open the drum, and valve mechanism in the vacuum duct interconnected with and operable by said manipulating means to close the vacuum duct from atmosphere subsequent to the closing of the drum and to re-open said duct to atmosphere prior to the opening of the drum.

6. Apparatus for manufacturing concrete comprising a framing, a tilttable revolvable drum having a single feed and discharge opening mounted in said framing, means operable from a driving unit of the apparatus for revolving the drum about its own axis, hand actuated means for tilting the drum about a horizontal axis, a revolvable closure member for the drum and capable of revolving therewith, means on the framing for suspending said closure member independently of said drum, vacuum creating means operable by the driving unit, a vacuum duct supported by the framing and connected to said vacuum creating means and to the drum closure member and adapted to communicate with the interior of the closed drum through said closure member, means carried by the framing for receiving ingredients for the drum and operable for delivering said ingredients into the drum and means for manipulating the drum closure member to close and open the drum, and valve mechanism in the vacuum duct interconnected with and operable by said manipulating means to close the vacuum duct from atmosphere subsequent to the closing of the drum and to re-open said duct to atmosphere prior to the opening of the drum.

7. Apparatus for manufacturing concrete comprising a framing, a tilttable revolvable drum having a single feed and discharge opening mounted in said framing, means operable from a driving unit of the apparatus for revolving the drum about its own axis, hand actuated means for tilting the drum about a horizontal axis, a revolvable closure member for the drum and capable of revolving therewith, means on the framing for suspending said closure member independently of said drum, vacuum creating means operable by the driving unit, a vacuum duct supported by the framing and connected to said vacuum creating means and to the drum closure member and adapted to communicate with the interior of the closed drum through said closure member, means carried by the framing for receiving ingredients for the drum and operable from the driving unit for delivering said ingredients into the drum and means for manipulating the drum closure member to close and open the drum.

8. Apparatus for manufacturing concrete comprising a framing, a tilttable revolvable drum having a single feed and discharge opening mounted in said framing, means operable from a driving unit of the apparatus for revolving the drum about its own axis, hand actuated means for tilting the drum about a horizontal axis, a revolvable closure member for the drum and capable of revolving therewith, means on the framing for sus-

pending said closure member independently of said drum, vacuum creating means operable by the driving unit, a vacuum duct supported by the framing and connected to said vacuum creating means and to the drum closure member and adapted to communicate with the interior of the closed drum through said closure member, means carried by the framing for receiving ingredients for the drum and operable from the driving unit

10

for delivering said ingredients into the drum, means for manipulating the drum closure member to close and open the drum, and valve mechanism in the vacuum duct interconnected with and operable by said manipulating means to close the vacuum duct from atmosphere subsequent to the closing of the drum and to re-open said duct to atmosphere prior to the opening of the drum. 80
